UNITED STATES PATENT OFFICE.

WILLIAM H. CLOAK, OF PHILADELPHIA, PENNSYLVANIA.

TRAIN-PIPE COUPLING.

No. 908,074.

Specification of Letters Patent.

Patented Dec. 29, 1908.

Application filed February 6, 1908. Serial No. 414,520.

To all whom it may concern:

Be it known that I, WILLIAM H. CLOAK, a citizen of the United States, residing in the city and county of Philadelphia, State of Pennsylvania, have invented a new and useful Train-Pipe Coupling, of which the following is a specification.

My invention relates to a new and useful train-pipe coupling which is adapted to automatically connect the fluid pipes of cars when they are brought together.

It further consists in providing a reciprocating valve for the coupling with means for actuating the same.

15 It further consists of providing a casing or closure for the operating parts.

It further consists of other novel details of construction, all as will be hereinafter fully set forth.

20 Figure 1 represents a side elevation of a car showing the train-pipe coupling in position. Fig. 2 represents an end view thereof with the car portion omitted. Figs. 3 and 4 represent partial elevations and partial sectional views, on an enlarged scale, showing the parts in different positions. Fig. 5 represents a sectional view showing the position of the valve within the plunger.

Similar numerals of reference indicate corresponding parts in the figures.

Referring to the drawings: In the connecting of the air or steam pipes of a train it is necessary, in order that this can be done automatically, to provide means which will be brought into proper alignment when the cars are brought together, and which will provide some means for automatically operating a valve or stop to permit the flow of the steam or air through the connection at the proper time. In the drawings I have shown a construction for accomplishing this purpose and which embodies my invention, but it will be evident that the arrangement of the parts may be varied, and other instrumentalities may be employed, which will come within the scope of my invention and I do not therefore desire to be limited in every instance to the exact construction as herein shown and described, but desire to make such changes as may be necessary.

50 In the drawings I have shown two coupling members, but it will be evident that any number may be employed and as the description of one of these members will serve for all I have deemed it unnecessary to describe but one.

1 designates a portion of the car having a draw-head 2 to which I preferably secure hangers 3 and 4. Connected with said hanger in any suitable manner, in the present instance by means of bolts, are the casings 5 and 6, although but a single casing may be employed if desired. Secured to said casings 5 and 6 are the frames 7 and 8, to each of which I secure a pipe 9, each having a coupling member 10 upon one end, to which is adapted to be secured the steam or air pipe 11 shown in dotted lines, Fig. 1.

Movably mounted in each of the casings 5 and 6 is the plunger 12, the same having a head 13 thereon to which is attached a stuffing box 14, which receives and moves upon the pipe 9, it being understood that said plunger 12 suitably fits an opening at the rear end of the casing 5 and that said plunger is provided with a lug which fits the casing 5 and forms a shoulder 15, between which and the end of the casing 5 is seated a spring 16 for holding said plunger in its normal position. The plunger 12 is provided with a suitable bore 17 and has formed on its inner wall a valve seat 18 and said plunger projects a suitable distance beyond the outer end of the casing 5 and is provided with a flange 19 adjacent its end. Suitably secured to said flange is an elastic casing 20 which is formed of any suitable material, such as rubber and which has a slightly rounded outer wall or end 21. Preferably carried by the said outer wall of the said elastic casing 20 is a head 22 which is provided with the rounded portion 23 adapted to be seated in a correspondingly formed recess in the head of a valve pin 24, said valve pin being suitably movable and guided in the bore 17 of the plunger 12 and the end of said valve pin being adapted to abut the stem 25 of the valve 26, while against the inner end of said valve there is a spring 27 which tends to normally hold said valve against its seat 18, the other end of said spring 27 abutting a suitable stop, in the present instance a pipe 28, which is fitted within the bore 17 of the plunger 12 and is movable therewith. Bearing upon the plunger 12 and seated within the elastic casing 20 is a spring 29 which is adapted to normally hold the said elastic casing extended in the position seen in Fig. 3, that is to say, with the end of the elastic casing a suitable distance from the end of the plunger 12.

110 The operation of the parts just described will be apparent:—The parts being in the

position seen in Fig. 3, the valve 26 is seated upon its seat 18 so that no passage of the air or steam can pass or escape through the coupling, but when two cars are brought together for the purpose of coupling the end of the coupling, upon one will abut the end of the coupling upon the other car, that is to say the curved heads 21 will be brought together and as the casing 20 is elastic, it will be suitably compressed, overcoming the tension of the spring 29 and moving in the head 23 with the valve pin 24, it being understood that the curved faces between said head 23 and the valve pin 24 permit of a certain amount of lateral movement of the parts. The forcing of the valve pin 24 moves inwardly the valve 26 removing the same from contact with its seat, against the tension of the spring 27 and as the cars continue to be brought together to the proper point the plunger 12 will be moved inwardly against the tension of the main spring 16 until the parts assume the position seen in Fig. 4, when the air or steam can pass through the coupling as desired. As soon as the cars are uncoupled the spring 27 returns the valve to its normal position while the elastic casing 20 is expanded by the action of the spring 29. At the same time the main spring 16 returns the plunger 12 and its parts to their normal position. In some instances it may be desirable to connect the coupling with the air hose in another manner and in order to permit of this I have provided the pipes 30 and 31 which are connected on opposite sides of the device with the plunger 12 and which are movable in slots 32 in the sides of the casing 5, said pipes 30 and 31 having a coupling 33 having air hose 34 connected therewith, which is on the car, so that when the parts are operated, as before described, the air will pass through the coupling device. By this means it will be seen that the air can pass through the pipes 30 and 31 when the valve is unseated by the coupling of the cars and can pass through the train system as desired. The valve 26 which I have shown is of the reciprocating style and I have shown the same formed with the grooves or passages 35 in the side walls to permit of the passage of the fluid therethrough when the valve is unseated.

Attention is called to the fact that the valve pin 24 is provided with a head or shoulder 36 which is so arranged as to abut the end 37 of the plunger when the valve pin 24 is moved in by the coming together of the cars for coupling purposes. By this means it will be seen that further inward movement of the valve 26 in the plunger is prevented and the entire pressure is removed from the sides of the elastic casing 20 and is applied to the plunger 12 which is moved inwardly, thereby compressing the spring 16. From this it will be understood that the

valve pin 24 serves not only to actuate the valve 26 to unseat the same but further acts upon the plunger to move the same and in which it is guided.

Having thus described my invention, **70** what I claim as new and desire to secure by Letters Patent, is:—

1. In a device of the character described, a plunger, a pipe on which said plunger is movable, a valve within and movable with **75** said plunger, and a valve pin guided in said plunger and adapted to be actuated to open said valve.

2. In a device of the character described, a plunger, a pipe on which said plunger is **80** movable, a valve within and movable in said plunger, a spring for normally holding said valve against its seat, a spring for holding said plunger in its normal position, a valve pin adapted to be actuated to open **85** said valve, and a casing surrounding said plunger whereby the operative parts of the device are protected.

3. In a device of the character described, a plunger, a pipe upon which said plunger **90** is movable, a spring for holding said plunger in normal position, a reciprocating valve within said plunger and movable therewith, a spring for normally holding said valve **95** against its seat, a valve pin having a portion thereof movable in said plunger and engaging said valve and a compressible casing connected with said plunger and surrounding the said valve pin.

4. In a device of the character described, **100** a plunger, a pipe upon which said plunger is movable, a spring for holding said plunger in normal position, a reciprocating valve within said plunger and movable therewith, a spring for normally holding said valve **105** against its seat, a valve pin having a portion thereof movable in said plunger and engaging said valve, a compressible casing connected with said plunger, and surrounding the said valve pin, and a casing surrounding **110** said plunger whereby the operative parts of the device are protected.

5. In a device of the character described, a plunger, a pipe on which said plunger is movable, a casing surrounding said plunger **115** for protecting the operative parts of the device, a spring for holding said plunger in its normal position and seated between said casing and said plunger, a valve movable in and with said plunger, a spring for holding **120** said valve normally against its seat, a valve pin having a portion thereof movable within said plunger and engaging said valve, an elastic casing connected with said plunger, and a spring for normally holding said elastic **125** casing in proper position.

6. In a device of the character described, a plunger, a pipe on which said plunger is movably mounted, a spring for normally holding said plunger in proper position, a **130**

- valve within said plunger, a spring for holding said valve against its seat, a valve pin having a portion thereof movable within said plunger and engaging with said valve, 5 a casing surrounding the extending portion of said pin, a head carried by said casing and engaging said valve pin, and a spring for normally holding said casing and said head in proper position.
- 10 7. In a device of the character described, a plunger, a pipe on which said plunger is movably mounted, a spring for normally holding said plunger in its proper position, a valve within said plunger and adapted to be reciprocated therein, a spring for normally holding said valve against its seat, a valve pin having a portion thereof projecting within said plunger and contacting with said valve, an elastic casing connected with said 15 plunger, a spring for normally holding said casing in proper position, a head carried by said elastic casing and having a curved face adapted to be seated in a correspondingly curved recess in said valve pin.
- 20 8. In a device of the character described, a plunger, a pipe on which said plunger is movably mounted, a stuffing box between said pipe and plunger, a casing surrounding said plunger and in which said plunger is movable, a spring between said casing and said plunger for holding the latter in normal position, a valve within said plunger adapted to be reciprocated therein, a spring for holding said valve normally against its seat, 25 a valve pin adapted to contact with said valve to actuate the same, a curved recess in said pin, a casing connected with said plunger and formed of elastic material, a spring for normally holding said elastic casing in proper position and a head carried by said casing having a curved face adapted to correspond with the curve of the recess in said valve pin.
- 30 9. In a device of the character described, a plunger movably supported, a valve movable within and movable with said plunger, a valve pin guided in said plunger and adapted to be actuated to open said valve, and a shoulder on said valve pin adapted to abut 35 said plunger in order to actuate the same.
10. In a device of the character described, a casing, a plunger slidably mounted therein, a port in said plunger, a valve normally closing said port, and means to unseat said valve to open said port when the plunger is operated. 55
11. In a device of the character described, a casing, a spring pressed plunger slidably mounted therein, a port in said casing communicating with the interior of said plunger, 60 a valve normally seated on said port, and means to unseat said valve when the plunger is moved against the tension of the spring.
12. In a device of the character described, 65 a plunger, means for movably supporting said plunger, a valve within and movable with said plunger, and a valve pin guided in said plunger and adapted to be actuated to open said valve.
13. In a device of the character described, 70 a plunger movably supported, a valve within and movable in said plunger, a spring for normally holding said valve against the seat, a spring for holding said plunger in its normal position, means adapted to be actuated to open said valve and a casing surrounding said plunger whereby the operative parts of the device are protected.
14. In a device of the character described, 75 a plunger movably supported, a spring for holding said plunger in normal position, a reciprocating valve within said plunger and movable therewith, a spring for normally holding said valve against its seat, means 80 having a portion thereof movable in said plunger and engaging said valve, and a compressible casing connected with said plunger and surrounding said engaging means.
15. In a device of the character described, 85 a plunger movably supported, a valve within and movable with said plunger, and a valve pin adapted to be actuated to open said valve and to engage with said plunger in order to actuate the same.
